UNITED STATES PATENT OFFICE.

JOSEPH P. DEVINE, OF BUFFALO, NEW YORK.

APPARATUS FOR DRYING THE COVERING OF ELECTRICAL CONDUCTORS OR THE LIKE.

1,420,367.

Specification of Letters Patent. Patented June 20, 1922.

Application filed February 20, 1920. Serial No. 360,175.

To all whom it may concern:

Be it known that I, JOSEPH P. DEVINE, a citizen of the United States, residing at Buffalo, in the county of Erie and State of

5 New York, have invented a new and useful Improvement in Apparatus for Drying the Covering of Electrical Conductors or the like, of which the following is a specification.

10 This invention relates to apparatus for removing moisture from the covering of cables, wire or other electrical conductors or analogous devices.

The objects of this invention are to provide an apparatus of this kind by means of which a coil or mass of covered wire or cable can be quickly heated by means of an electric current passing through the same, to effect a rapid drying of the covering and 20 which is so constructed that the ends of the conductor or conductors to be dried can be readily connected with and disconnected from a suitable supply of electric current; also to improve methods and apparatus of 25 this kind in other respects hereinafter specified.

In the accompanying drawings:

Fig. 1 is a central sectional elevation of an apparatus embodying the invention, by 30 means of which the process forming a part of this invention may be carried out.

Fig. 2 is a sectional plan view thereof on line 2—2, Fig. 1.

Fig. 3 is a similar sectional plan view 35 thereof on an enlarged scale showing means for making electrical connections.

The apparatus disclosed is primarily intended for use in drying the paper covering which is generally first placed upon the 40 wires, cables or other electrical conductors, and which after being thoroughly dried, is impregnated with an insulating material. The invention, however, may be used for drying covering other than paper.

45 In the apparatus shown A represents a vacuum or drying chamber which may be of any suitable form, that shown being substantially cylindrical and open at the top to permit the drums on which the covered 50 conductor is wound to be placed into the chamber. The upper portion of the chamber is closed by means of a cover B which may be held in place on the drying chamber by the usual bolts 3 or the like. The 55 air may be exhausted from the drying chamber through a pipe C. D represents the

drums on which the covered wire, cable or other conductor is wound, the ends d of the conductor projecting beyond the drums.

In order to conduct electricity to the conductors wound on the drums, suitable bus bars or other connectors are arranged within the drying chamber, to which the ends of the conductors on the drums may be connected. In the construction shown for this

purpose, two pairs of bus bars E are provided which are supported upon the wall of the drying chamber by any suitable means such as brackets F, F', F², which may be made of insulating material or which may be otherwise insulated from the bus bars. In the construction shown, the bus bars are slidable relatively to the supporting brackets therefor, this being accomplished by means of pins G extending through the brackets and through the bus bars, and springs g are provided which press the bus bars of each pair yieldingly toward each other, the springs shown being arranged around the pin G. By means of this construction, if a wire d is forced between the bus bars, the springs will yieldingly press the bars into engagement with the wire and thus form a good contact or connection through which the current may be conducted to the wires. The bus bars are connected to suitable conductors g' which in the construction shown extend through insulating bushings g² in the wall of the drying chamber. The advantages of the bus bar construction shown are that any number of conductors may be placed between the bus bars and the conductors may be connected to the bus bars at any desired portions thereof. Other means may be provided for supplying electric current to the conductors on the drums. The current flowing to the bus bars may be controlled by any suitable well known means so that the temperature of the wires may be regulated

95 as desired. By means of the arrangement of the bus bars described, any number of coils may be connected with the supply of current and it is only necessary to provide a single connection extending through the 100 wall of the drying chamber for each bus bar, thus reducing the possibility of leaks to a minimum.

The apparatus described is very efficient in the amount of power consumed for the 110 reason that the heat is applied directly to the conductors, and a great saving in time

required to dry the covering is also effected by means of the apparatus. The use of vacuum for removing moisture also greatly facilitates the drying of the wire covering.

5 I claim as my invention:

1. In an apparatus for drying the covering of electrical conductors, the combination of a drying chamber from which air may be exhausted and electrical connecting means which extend substantially throughout the length of said chamber and to which a plurality of said conductors may be connected for passing a current of electricity through said conductors for heating the same.

10 2. In an apparatus for drying the covering of electrical conductors, consisting of a drying chamber from which air may be exhausted, electric connecting means which extend substantially throughout the length of said chamber and to which a plurality of said conductors may be connected for passing a current of electricity through said conductors for heating the same, and a 15 single pair of terminals extending through the chamber walls for supplying current to said connecting means.

3. In an apparatus for drying the covering of electrical conductors, consisting of a drying chamber adapted to receive a drum on which a covered conductor is wound, means through which air may be exhausted from said chamber, and electrical connectors in said chamber and including two members, 30 one of which is yieldingly pressed toward the other member and between which the 35

ends of the conductors may be yieldingly held for causing the conductor to be heated by a current of electricity passing through the same.

4. In an apparatus for drying the covering of electrical conductors, consisting of a drying chamber adapted to receive a drum on which a covered conductor is wound, means through which air may be exhausted from said chamber, and electrical connectors in said chamber including bus bars extending substantially throughout the height of the chamber, and to which the ends of the conductors may be connected for heating the conductors by a current of electricity flowing through the same.

5. In an apparatus for drying the covering of electrical conductors, consisting of a drying chamber adapted to receive a drum on which a covered conductor is wound, means through which air may be exhausted from said chamber, and electrical connectors in said chamber including bus bars extending substantially throughout the height of the chamber, each bus bar comprising two members yieldingly pressed toward each other and between which the ends of the conductor may be yieldingly held for causing the conductor to be heated by a current of electricity passing through the same.

Witness my hand this 16th day of January, 1920.

JOSEPH P. DEVINE.
